UNITED STATES PATENT OFFICE.

ARTHUR G. ROGERS, OF MERIDEN, CONNECTICUT, ASSIGNOR TO C. ROGERS & BROS., OF SAME PLACE.

DESIGN FOR A HANDLE FOR SPOONS, &c.

SPECIFICATION forming part of Design No. 27,589, dated August 31, 1897.

Application filed July 20, 1897. Serial No. 645,267. Term of patent 7 years.

To all whom it may concern:

Be it known that I, ARTHUR G. ROGERS, of Meriden, in the county of New Haven and State of Connecticut, have invented a new 5 Design for the Handles of Spoons, Forks, &c.; and I do hereby declare the following, when taken in connection with the accompanying drawing and the letters of reference marked thereon, to be a full, clear, and exact description of the same, and which said drawing constitutes part of this specification, and represents a face view of a spoon embodying my design.

This invention relates to a design for the 15 handles of spoons, forks, and like articles of table-service; and the design consists in the configuration and ornamentation of the handle, as herein shown and described.

The handle tapers gradually from its lower 20 end, where it is joined to the body A by a scroll ornament a, to about midway of its length, where its contour is broken by three scrolls B, which form a scalloped projection, beyond which the handle expands outward and then

inward, its contour being formed by long 25 overlapping scrolls C D E, united at the top by a crowning ornament F. Upon each side of the surface of the handle from its lower end to the scrolls B is a narrow beading G, which is continued, broken somewhat by intersection with the upwardly-turned scrolls C D E, and continues around the rounded top of the handle in gradually-enlarged beads, this beaded border inclosing a plain panel H, running throughout the length of the handle, 35 all as shown in the accompanying illustration.

I claim—

The design for handles of spoons forks, &c., as herein described and shown in the accompanying illustration.

In testimony whereof I have signed this specification in the presence of two subscribing witnesses.

ARTHUR G. ROGERS.
